US0D1051315S

(12) **United States Design Patent** (10) **Patent No.:** **US D1,051,315 S**
(45) **Date of Patent:** **** Nov. 12, 2024**

(54) **HANDHELD FAN**

(71) Applicant: **Guangdong Aoyun Technology Co., Ltd.**, Huizhou (CN)

(72) Inventor: **Xueping Zhu**, Shenzhen (CN)

(73) Assignee: **Guangdong Aoyun Technology Co., Ltd.**, Huizhou (CN)

(**) Term: **15 Years**

(21) Appl. No.: **29/920,979**

(22) Filed: **Dec. 14, 2023**

(51) LOC (14) Cl. **23-03**

(52) U.S. Cl.

USPC **D23/335**; D23/370

(58) **Field of Classification Search**

USPC D23/332, 370, 381, 382

CPC F04D 25/084; F04D 25/086

CLAIM

The ornamental design for a handheld fan, as shown and described.

DESCRIPTION

FIG. 1 is a front perspective view of a handheld fan, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the handheld fan, which form no part of the claimed design.

1 Claim, 8 Drawing Sheets
